UNITED STATES PATENT OFFICE.

RAYMOND T. ASHLEY, OF RENO, NEVADA.

LINK.

Application filed January 30, 1920. Serial No. 355,367.

To all whom it may concern:

Be it known that I, RAYMOND T. ASHLEY, a citizen of the United States, residing at Reno, in the county of Washoe and State 5 of Nevada, have invented certain new and useful Improvements in Links, of which the following is a specification.

This invention relates to a new, novel and useful improvement in links, and the same 10 may be adapted to many uses such as a conveyor belt link, a tractor link of the self-laying track type, a sprocket chain or any other similar use.

The principal object of this invention is 15 to provide a link which will be a unit structure.

Another object of this invention is to produce a link which will be comparatively free from friction.

20 Another object is to produce a link which will be cheap to manufacture.

Another object is to produce a link which may be readily replaced should breakage occur.

25 Another object is to produce a link wherein in the ordinary assembling bolts and nuts have been eliminated.

Other objects and advantages of this invention will be seen as the description 30 proceeds.

In this specification and the annexed drawings, the invention is illustrated in the form considered to be the best, but it is to be understood that the invention is not 35 limited to such form, because it may be embodied in other forms, and it is also to be understood that in and by the claims following the description it is desired to cover the invention in whatsoever form it may be 40 embodied.

In the drawings:

Figure 1 is a top plan view of three links in assembled position.

45 Figure 2 is a cross section taken on the line II—II of Figure 1.

Figure 3 is a perspective view of one of my links partly in cross section.

Figure 4 is a perspective view of a rocker bar.

50 Referring to the drawings, like numerals refer to corresponding parts in the several views.

The numerals 5, 6 and 7 refer to links as a whole. These links are provided with a 55 flat central portion 8 and are provided along their outer margins with tracks 9 and 11

formed integral with the flat portion 8, and raised above the plane of the same are two inclined portions 12 and 13, provided with an arcuate end 16. These portions 12 and 13 60 are connected by a bridge portion 14, which is crescent shape in cross section, also of the same contour as the portion 16. This portion 14 is formed on an arc, as shown at 65. A tongue 18 is formed integral with the flat portion 8 and upon the opposite end from that of the bridge. At 19 I show a curved portion following the contour 16 but spaced therefrom. The numeral 21 70 refers to a rocker bar formed upon one side upon the arc of the outer circle 16, as shown at 22. Its opposite side is formed upon an epicycloid curve, as shown at 23.

In assembling a chain composed of my 75 links, a rocker bar is placed against the curved portion 17 so that the outer curve 22 of the rocker extends toward the hook 18. The hook of the link next to be attached is then guided through the opening 24 and around the rocker bar which will then be 80 become enclosed by the bridge 14 and the hook 18 of the adjacent link. This assembly will result in a structure as shown in Figure 2, consequently the rocker 21 will take the 85 position shown at A Figure 2 when the links are in alignment. When the links are bent as in passing around a sprocket, shown in dotted lines in Figure 2, the rocker will take the position B, Figure 2.

By providing this link contact, it will be 90 seen that I have eliminated the usual construction which would be present were the member 14 circular in form.

It will thus be seen that I have formed a 95 link, which when assembled with other links, forms an efficient chain without the necessity of other parts. When this chain is passing over a sprocket wheel, the teeth thereof will contact with the portion 16 or with the hook 18 as the case may be, thereby providing an efficient driving means, and if it is desired to use the same upon a sprocket wheel, the tracks 9 and 11 will form a continuous supporting surface for the usual tension wheels, while the driving sprocket 105 wheels operate as before described.

Having thus described my invention what I claim as new and desire to secure by Letters Patent of the United States is as follows:

110 1. In a link, a hook at one end, a bridge portion at the other end, and a connection

between those members, said members and connection formed integrally, and said bridge portion provided with an arcuate depression for the reception of a rocker member, and a rocker member adapted to rest in the space produced by said depression between the hook and the bridge of an interlocking link.

10 2. In a link, a flat portion, tracks adjacent the outer margins of said flat portion, a hook at one end of said link and between said tracks, a bridge portion at the other end of said link formed integrally therewith, said bridge portion being provided with an arcuate depression for the reception of a rocker member.

15 3. In a link, a flat portion, tracks adjacent the outer margin of said flat portion, an up-standing hook at one end of said link midway between said track portions, inclined portions extending toward the opposite end of said link from said hook, a bridge por-

tion connecting said inclined portions and integral therewith, said inclined portions 25 and said bridge having an arcuate end contour, said bridge portion having an arcuate depression on its inner side, and a rocker bar having an epicycloid surface, said bar being adapted to lie within said arcuate depression of said bridge portion.

4. In a link, a hook at one end, a bridge portion at the other end, and a connection between those members, said connection provided with longitudinal tracks at its outer edges, said parts formed integrally, and said bridge portion having an arcuate depression for the reception of a rocker member, and a rocker member adapted to rest in the space produced by said depression between the hook and the bridge of an interlocking link.

40 In testimony whereof I affix my signature.

RAYMOND T. ASHLEY.
